UNITED STATES PATENT OFFICE.

WILLIAM F. J. CASEY AND GUSTAVE CAVIN, OF KINGSTON, ONTARIO, CANADA.

LOCOMOTIVE DRIFTING-THROTTLE.

1,198,415.

Specification of Letters Patent. Patented Sept. 19, 1916.

Application filed October 6, 1914. Serial No. 865,272.

To all whom it may concern:

Be it known that we, WILLIAM F. J. CASEY and GUSTAVE CAVIN, both citizens of the Dominion of Canada, and residents of the city of Kingston, in the Province of Ontario and Dominion of Canada, have invented certain new and useful Improvements in Locomotive Drifting-Throttles, of which the following is a full, clear, and exact description.

This invention relates to improvements in drifting throttles for locomotives.

A further object is to provide a valve entirely automatic and positive in its operation that will admit a limited amount of steam to the valve chest for cooling purposes as soon as the throttle is closed if the locomotive is in motion, and will cut off this supply of steam when the motion of the locomotive ceases.

Another object is to provide a device which may be connected to any suitable moving part of a locomotive so as to be governed by the movement of the locomotive.

Various other objects and advantages of the device will be apparent from the following description.

At the present time, the majority of locomotives use superheated steam with the result that the normal temperature of the relatively moving parts exposed to the steam is very high. When the throttle is closed and the locomotive still in motion, friction develops very high temperatures of the working surfaces with destructive and disastrous results. The principal cause of this is that there is no flow of steam through the exhaust outlets to carry off frictional heat, so that a rise of temperature occurs very rapidly.

The cessation of steam flow is usually accompanied by a cessation of lubricating oil flow, so that with the high normal temperature, the working parts become almost instantly dry. This condition has been discussed at great length in various technical works and in various prior patent specifications, so that further exposition of the subject is unnecessary. The patented inventions which have been produced are of numerous varieties, but in the main may be divided into two classes; those which work semi-automatically, that is to say, require some initial manually performed starting or stopping operation, and those which work either entirely automatically or semi-automatically using as a motive force the vacuum

drawn in the locomotive cylinders when the engine is in motion. While a number of these devices have been placed in operation and may be theoretically perfect, it has been found in practice that there is room for considerable improvement. Experience has demonstrated certain essentials, namely, the device must be entirely automatic in its action, must be of simple and durable construction, and must be so connected with the locomotive that it cannot be inadvertently rendered inoperative. If the device is not purely automatic in its action, the engineer may neglect to start the same in operation, with the possible resultant burning of the cylinders and valves, or may neglect to stop the same with the result that after the locomotive is stopped, a supply of steam gradually accumulates in the cylinders sufficient to move the engine. If the device depends for its motive force upon vacuum drawn in the cylinders, it is apparent that the vacuum may be destroyed by an open or broken cylinder cock or by various other means, so that the valve is rendered inoperative. From this, the necessity of the foregoing essentials mentioned will be apparent.

The present invention meets these essential features, and provides a valve of the simplest construction, depending for its motive force upon fluid pressure generated by the movement of the engine in a continuously operating compressor, so arranged that it cannot be inadvertently stopped. The device thus operates automatically by positive pressure, and not by a negative pressure, so that it will be absolutely reliable.

In the drawings which illustrate the invention: Figure 1 is a fragmentary side elevation of a locomotive illustrating diagrammatically the attachment of the drifting throttle. Fig. 2 is a vertical sectional view of the throttle.

In Fig. 1, the arrangement of the parts is diagrammatically shown. The valve will preferably be somewhere near the center line of the locomotive between the valve chests with a supply to each valve chest, instead of on the outside as shown.

Referring more particularly to the drawings, 11 designates the boiler of a locomotive, 12 the steam chest, and 13 the steam supply pipes leading from a superheater in the smoke box to the valve chests 12, and 14 designate the valve gear rocker.

The device consists generally of a valve

16 having a steam supply pipe 17 leading directly from the boiler, and a second steam supply pipe 18 leading from some point between the throttle and valve chest. The 5 valve is connected by a pipe 19 with a small compressor 20 continuously operated by the valve gear rocker 14 or other suitable part of the engine. The valve is finally connected of pipes 21 with the valve chests. The 10 valve 16 is of extreme simplicity, and consists of a casing 22 having at the top suitable connections 23 for the steam delivery pipes 21. A valve 25 is arranged in the body between the supply pipe 17 and the delivery pipes 21, and is arranged to remain normally closed both by the action of gravity and by boiler pressure on its larger upper surface. The stem 26 of this valve depends into the lower part of the casing, 15 which is separated from the steam supply and delivery passages. In the lower part of the casing is a free-moving piston 27 adapted on its upward movement to engage the valve stem 26 and lift the valve 25. The 20 space above the piston is provided with a vent 28 to permit the escape of any fluid leaking past the piston.

The bottom of the casing 22 is closed by a head 29 having a passage 30 connecting the 30 pipe 19 with the space under the piston 27. A branch passage 31 extends laterally from the passage 30 and is provided with a plurality of outlets 32 normally isolated from the passage 30 by a valve 33, the spindle 34 of which traverses the passage 30 and extends into a small cylinder 35 on the opposite side thereof. The valve 33 may be maintained in closed position by a spring 36. A piston 37 is provided in the cylinder 35 35 and may be held out of engagement with the valve stem 34 by a spring 38 and by pressure flow through the passage 39 leading from the passage 30 into the cylinder 35. The steam may be supplied on top of the 40 piston 37 through the pipe 21 to move the piston in the cylinder 35 and open the valve 32. The piston at its extreme movement rests on the seat 40 and prevents leakage of steam pressure through the passage 39 to 45 the piston 27 or to the outlets 32.

The operation of the device is extremely simple and will be readily understood. The position of valve parts shown in the drawings is that which occurs when the locomotive is running with the steam supplied to the cylinders in the usual manner. The exertion of pressures is as follows:—Steam from the supply pipe 17 maintains the valve 25 closed, so that no steam flow occurs 50 through the pipes 21. Steam pressure from one or both steam supply pipes 13 flowing through the pipe 18 acts against the head of the piston 37 and holds the same on the seat

40, thus holding the valve 33 open. This condition occurs against the action of the 65 springs 36 and 38. Fluid pressure generated by the compressor 20 flows through the pipe 19 to the passage 30, and from the passage 30 through the open valve and out to the atmosphere through the opening 32, so that 70 in this condition, the compressor is running idle and utilizing no more power than that required to overcome friction. When the engineer closes his throttle, the steam supply and pressure are cut off through the 75 pipe 18, and in fact, operation of the engine pistons may tend to produce a partial vacuum in this pipe. The spring 36 closes the valve 33 and the spring 38 presses the piston 37 off its seat 40, relieving the valve 80 stem 34 of any work in moving the piston. The only escape for the fluid pressure supplied by the compressor 20 is now through the passage 30 to the underside of the piston 27. The piston 27 rises, and engaging the 85 stem 26 of the valve 25, raises this valve against the boiler pressure, owing to the much greater area of the piston 27. Non-superheated steam now flows from the pipe 17 through the pipes 21 to both valve chests 90 12, and supplies sufficient steam to partially lubricate the working surfaces and to carry off the heat generated by friction. This supply of steam also has the effect of partially relieving any vacuum in the engine 95 cylinders. It will be apparent that a certain amount of this steam pressure will now flow through the pipe 18 and press against the head of the piston 37, but owing to the small flow of steam and its subsequent expansion, 100 the pressure of air flowing through the passage 39 against the underside of the piston will be sufficient to keep it free from the valve stem 34.

As long as the locomotive remains in motion, the compressor supplies fluid pressure to maintain the piston 27 elevated and the valve 25 open. As soon, however, as the locomotive stops, the supply of fluid pressure ceases and leakage past the piston 27 soon 110 enables boiler pressure and the action of gravity to close the valve 25, and cut off steam flow to the valve chests through the pipes 21. Leakage past the piston 27 escapes through the vent 28, so that there is 115 no resistance to the rise of the piston when steam is next cut off at the throttle. As soon as steam is turned on at the throttle to start the locomotive, pressure through the pipe 21 returns the valve 33 and piston 37 to the 120 positions shown in Fig. 2.

While the compressor has been shown attached for continuous operation to the rocker of the outside valve gears at present in general use, it is obvious that it may be located 125 at any other suitable point.

It may be mentioned that the use of the spring 38 is not essential as this spring is merely a supplement of the steam pressure.

Having thus described our invention, 6 what we claim is:—

1. In a device of the class described, a normally closed differential valve, continuously discharging pressure fluid adjacent thereto exhausting freely to the atmosphere, 10 and automatically operable means for diverting said pressure fluid to open said valve comprising a normally closing valve for controlling the exhaust of said pressure fluid and variable pressure means for controlling the opening of said second named valve.
2. In a device of the class described, a normally closed differential valve, continuously discharging pressure fluid adjacent 20 thereto exhausting freely to the atmosphere, and automatically operable means for diverting said pressure from exhausting to open said valve and back to exhausting comprising a spring closed valve for controlling the exhaust of said pressure means for rendering said spring operative and inoperative to close said second-named valve.
3. In a device of the class described, a normally closed differential valve, continuously discharging pressure fluid adjacent thereto exhausting freely to the atmosphere, and automatically operable means for diverting said pressure to open said valve comprising a secondary differential valve 30 controlling the exhaust of said pressure, means operable upon said secondary valve

in one direction to normally close the exhaust and means operable in another direction to maintain said exhaust open.

4. In a device of the class described, a 40 normally closed differential valve, a pressure pipe communicating with said valve, an exhaust valve to the atmosphere for said pressure pipe normally open, a high pressure steam pipe, and means whereby cessation of pressure in the high pressure steam pipe closes said exhaust valve whereby pressure from said pressure pipe opens said differential valve.

5. In a device of the class described, a 50 casing provided with a steam supply pipe, steam conducting pipes communicating therewith, a valve held normally closing said supply pipe, a piston operatively connected with said valve to open it, a pressure 55 pipe communicating with said piston, an exhaust valve to the atmosphere for said pressure pipe normally open, a high pressure steam pipe, and spring means whereby cessation of pressure in the high pressure 60 steam pipe closes said exhaust valve whereby pressure from said pressure pipe moves said piston and opens the steam supply valve to permit steam to pass into the steam conducting pipes.

In witness whereof, we have hereunto set our hands, in the presence of two witnesses.

WILLIAM F. J. CASEY.
GUSTAVE CAVIN.
